UNITED STATES PATENT OFFICE.

GEORG FORNER, OF BERLIN, GERMANY.

STEAM PLANT.

Application filed June 27, 1923. Serial No. 648,073, and in Germany June 28, 1922.

This invention relates to steam turbines or other motors operating in conjunction with steam accumulators of highly varying pressure. In plants embodying such units an approximately constant quantity of steam is usually supplied by the boiler, the steam which is not used by the turbine at moderate load being used for charging the accumulator and the additional quantity of steam required by the turbine at higher load being obtained by withdrawing steam from the accumulator and supplying the turbine therewith. In the turbine plants of known type the charging steam is taken from an intermediate stage of the turbine and the steam withdrawn is admitted to the same stage or to a following intermediate stage, the stage receiving steam from the accumulator having a set of nozzles and series control therefor of which only so many nozzles being open behind the point of withdrawal that the pressure in front of these nozzles differs from the accumulator pressure merely the amount of the unavoidable loss of pressure.

This arrangement presents the inconvenience that the pressure at the point of withdrawal must participate in the great variations of pressure in the accumulator so that very great fluctuations are produced in the head of the two turbine stages adjacent to the point of withdrawal. On account of these strong variations of the head in the two stages adjacent to the point of withdrawal, the average efficiency of these stages is unfavorably influenced. A turbine of this type uses, therefore, in all, more steam than a turbine without accumulator otherwise of the same type, this surplus consumption amounting in most cases to over 5%. The improvement in efficiency of the boiler due to the uniform demand in consequence of the accumulator is reduced this amount.

This invention has for its object to reduce this loss to that which is absolutely unavoidable and this result is attained by making the variations of pressure in the turbine to a great degree independent of variations of pressure in the accumulator. With this object in view one or several elements are inserted in connections between the accumulator and the turbine, which regulate the flow of steam according to requirements.

In one form of the invention steam, taken from the accumulator at a higher load on the turbine, is supplied to a turbine stage

which, in the direction in which the steam flows, is situated behind the stage from which the steam for charging the accumulator is taken, none of these two stages having an automatic series governing of nozzles. In this case the pressures at the point of withdrawal and at the point of admission are independent of the accumulator pressure and the only condition which has to be fulfilled is that the pressure at the point of withdrawal must be greater than the accumulator pressure and the accumulator pressure must be greater than the pressure at the point of admission. Although in this case a loss from throttling is produced which is greater than the loss in commonly used arrangements, the influence of this loss on the consumption of steam is only a slight increase of the same as this loss from throttling occurs in only a small part of the steam and occurs only during discharge of the accumulator. In accordance with well known physical laws part of this loss is recuperated in the low-pressure part of the turbine. The remaining moderate loss is more than compensated for by the influence of the decreased variations of head to which the stages are submitted which are adjacent to the point of withdrawal and to the point of admission. These smaller variations of head give these stages a degree of efficiency which differs only slightly from the maximum degree. The average degree of efficiency of a turbine of this type is consequently but little less than that of an equivalent turbine without accumulator. The increase of the consumption of steam may be estimated at about 1% so that the invention affords an improvement by at least 4% of the steam consumption compared with that of the commonly used arrangements.

The invention will be best understood from a consideration of the following detailed description taken in connection with the accompanying drawing forming a part of this specification, with the understanding that while on the drawings several embodiments of the invention are disclosed, the invention is not confined to any strict conformity with the showing of the drawings, but may be embodied in any manner which does not make a material departure from the salient features of the invention.

In the drawings:—

Fig. 1 shows diagrammatically a preferred form of the invention.

Fig. 2 shows diagrammatically a turbine arranged according to a second form of the invention.

Fig. 3 shows diagrammatically a turbine arranged according to a third form of the invention.

Fig. 4 shows diagrammatically a turbine arranged according to a fourth form of the invention.

10 Fig. 5 shows diagrammatically a pressure operated valve for use in place of speed controlled valves of certain modifications.

According to Fig. 1 in normal operation, a practically constant quantity of steam is supplied from the boiler *k* through the conduit *a* and the port *h* of the slide-valve *c* to the high-pressure nozzles of the turbine *t* which are not specially automatically governed. The position of the slide-valve *c*, as shown corresponds with the condition that the turbine consumes exactly the quantity of steam supplied by the boiler. If the speed of the turbine increases, due, for example, to decrease of load so that it requires

25 less steam than the boiler supplies, the governor pulls the slide-valve *c* to the left so that steam from an intermediate stage, in the case shown in Fig. 1 from the first chamber *b*, flows into the accumulator *s* through the port *f* of the slide-valve. If the load on the turbine increases so much that the steam consumption becomes greater than the quantity of steam supplied by the boiler *k* the speed governor displaces the slide-valve *c* so far to the right that the withdrawal of steam from chamber *b* is cut off, steam flowing however from the accumulator *s* through another port *g* of the slide-valve *c* into a lower stage, in Fig. 1, chamber *d*.

40 If the accumulator *s* is completely charged and simultaneously, the load decreases so much that the required steam consumption is less than the quantity of steam supplied by the boiler, the slide-valve *c* is pulled to the left so that the port *h* is also shut off partly or entirely and the fresh steam which flows through pipe *a* is cut off partly or entirely.

50 Instead of a slide-valve three throttling valves may be used, which are controlled from a common shaft operated by the speed governor. Instead of the direct regulation of the slide-valve or other means by the governor, indirect regulation by oil pressure or by any other well known auxiliary device is preferably selected.

55 If the quantity of steam supplied by the boiler is occasionally for some time greater or smaller than the normal average quantity, hand operated auxiliary valves *z* are preferably used to conduct fresh steam to separate high-pressure nozzles. As the separate nozzles work generally under other conditions of pressure than the normal noz-

zles it is advisable to design them with different dimensions, for instance other cross sections, angles, expansion ratios, etc. In the cases where the limits between which the accumulator pressure varies are very wide the head of the stage or stages situated between the point of withdrawal *b* and the point of admission *d* will be very great. In order to reduce this head the accumulator *s* is separated from the chamber *d* as indicated in Fig. 1 in dash lines, and the steam taken from the accumulator *s* during the discharge is supplied to the limited space *e* from which it flows through separate nozzles which may also be of other dimensions than the normal nozzles, thence to the following disk. This affords the advantage that a higher pressure may be maintained in the chamber *d* so that the head occurring between the chambers *b* and *d* is reduced. This head remains now almost unvaried and the variation of head occurs in the next following stage.

The further advantage is added to the advantages mentioned that only one slide-valve or one shaft with three throttling valves is required and that they need be driven only from the speed governor (series governing of nozzles and influencing of the governor by the accumulator pressure being omitted), whereby the security of service and the sensitiveness of the governing are increased. The omission of the automatic series governing of nozzles presents the further advantage that the nozzle cross sections in all stages are constant for each stage so that by reading the pressures and the temperature in front of the nozzles it may be ascertained at any moment how much steam is supplied by the boiler and how much steam is withdrawn from the turbine or supplied to the same from the accumulator. Such a method of measuring is practically impossible with automatic governing of nozzles unless a separate pressure gauge is arranged behind each of the nozzle valves which indicates the state of throttling of the valve; but even then it would not be possible to calculate accurately from the pressures and temperatures the exact quantity of steam which flows through when a valve is throttling strongly. This advantage which results from the omission of series governing of nozzles, must not be valued too low as it offers a simple and easy possibility to control the service without tedious and expensive measurements of steam consumption.

125 It will be seen from the above description that when the turbine load is substantially at average value so that a balance obtains between motor plant load and motor plant steam energy supply, the parallel paths for steam to and from the turbine and accumu-

lator are wholly cut off so that there is no communication between the accumulator and the turbine. It is a characteristic of this invention that the motor operates at a substantial value of balance of plant load while communication is wholly cut off between the accumulator and motor. This characteristic combined with throttling means in the communications to make the motor substantially independent of variations of pressure in the accumulator make a highly efficient motor plant.

The embodiment shown in Fig. 2 is similar to the embodiment described above with reference to Fig. 1 and is preferably used when the highest accumulator pressure is so near the boiler pressure that the head between fresh steam pressure and the pressure in the chamber *b*, which in the first embodiment must always be greater than the accumulator pressure, is not great enough to be economically utilized in a turbine stage. In this case the steam for charging the accumulator at low load is taken from the fresh-steam pipe and when the accumulator discharges at a higher load the steam from the accumulator is conducted into an intermediate stage of the turbine in which the pressure is always lower than the accumulator pressure. The regulation is effected, as in the first embodiment, merely by the speed governor, which controls the deviation of the fresh steam to the accumulator, the amount of the fresh steam supplied to the first stage during charging and the discharging from the accumulator into an intermediate stage.

In the embodiment shown in Fig. 2 an almost unvarying quantity of steam flows from boiler *k* through the pipe *a* and through port *h* of slide-valve *c* to the high-pressure nozzles of the turbine *t*. The slide-valve *c* is shown in Fig. 2 in the position at which the quantity of steam consumed by the turbine *t* is equal to that supplied by the boiler *k*. If the turbine speed increases, due, for example, to decreased load, the slide-valve *c* is pulled to the left, the fresh-steam pressure in front of the high-pressure nozzles decreasing so that less steam flows into the turbine and the excess part of the steam supplied by the boiler flows through the port *f* of the slide-valve into the accumulator *s*. When the load increases so that the turbine consumes more steam than the boiler supplies the slide-valve is pushed so far to the right that the port *f* of the slide is shut off, the port *h* remaining fully open, and steam flows from the accumulator *s* through port *g* of the slide-valve into the chamber *d* of the turbine. For the slide-valve three throttling valves operated from a common shaft may be substituted and auxiliary valves adapted to be operated by hand might be arranged for the high-pressure nozzles. Under the

same conditions as mentioned with regard to the first embodiment the steam supplied from the accumulator to an intermediate stage of the turbine may be conducted into a separate chamber *e* in front of separate nozzles of this stage, the separate nozzles being also of different dimensions than the other nozzles of this stage.

In Fig. 3 a third embodiment is shown. From the boiler *k* an approximately uniform quantity of steam flows through the pipe *a* to the turbine *t* traversing a number of controlled valves *i* of which only one is shown in the drawing. If the load sinks so that the quantity of steam consumed by the turbine is smaller than that supplied by the boiler the control valve *l* opens and lets steam flow from the fresh-steam pipe *a* through the branch pipe *m* into the accumulator *s*. When the load on the turbine increases so much that the quantity of steam supplied by the boiler *k* is no longer sufficient, the valve *n* opens and lets steam flow over from the accumulator *s* through the pipe *o* into a chamber *d* of the turbine *t*. The valves *i*, *l*, *n* may be operated from a common shaft *q* by the speed governor. The quantity of steam admitted through valve *n* from the accumulator to the turbine chamber *d* may again be conducted into a separate compartment *e* of this chamber in front of separate nozzles which may be of different dimensions than the other nozzles of the same stage. Instead of the valve *l* operated by the governor an automatic pressure operated valve might be inserted into the branch pipe *m* which opens when the pressure in pipe *a* increases beyond an adjustable limit owing to the reduced steam consumption of the turbine. Such an automatic pressure operated valve is shown in Fig. 5 and designated with reference character *l*^a. The valve is operated by means of a piston 10 acted upon on one side by a spring 12 and on the other side by fluid pressure in a chamber 13. In the modification shown steam acts directly upon the piston, being transmitted through tube 14. Upon increase of pressure in conduit *a*, piston 10 is moved upwardly and raises the movable portion of valve *l*^a thereby increasing the flow through pipe *m* to the accumulator. Upon decrease of steam pressure in pipe *a*, piston 10 is moved downwardly under the action of spring 12 to close valve *l*^a and allow less steam to flow to the accumulator.

When the highest accumulator pressure is nearly equal to the boiler pressure, the pressure in the first chamber of the turbine being however essentially lower than the accumulator pressure, a fourth embodiment is preferably used which is shown in Fig. 4. In this embodiment steam for charging the accumulator, at a low steam consumption of the turbine is taken from the fresh-steam pipe 130

and the steam which is withdrawn from the said motor, and means responsive to the speed of said motor and operating to hold both said throttling valves closed at a given speed, to open the first-mentioned throttling valve when the speed of the motor increases above said given speed and to open the second-mentioned throttling valve when the speed of the motor decreases below said given speed.

5 and the steam which is withdrawn from the said motor, and means responsive to the speed of said motor and operating to hold both said throttling valves closed at a given speed, to open the first-mentioned throttling valve when the speed of the motor increases 70 above said given speed and to open the second-mentioned throttling valve when the speed of the motor decreases below said given speed.

10 and through one or several controlled valves i , of which only one is shown in the drawing, to the high-pressure nozzles of the turbine t . As long as the turbine consumes exactly as much steam as is supplied by the boiler 15 the valves l and n remain closed. If the speed of the turbine increases the speed governor opens the valve l through the intermediary of the common shaft q , and the steam in excess will flow over through the 20 pipe m into the accumulator s . When the speed decreases so much that the steam supplied by the boiler is no longer sufficient the speed governor again closes the valve l and opens successively the valves n , of which 25 only one is shown in the drawing, so that steam may flow from the accumulator s through the pipe o to separate high pressure nozzles. These separate nozzles may be of different dimensions than the nozzles arranged 30 behind the pipe a . Instead of the valve l an automatic pressure operated valve similar to valve l^a of Fig. 5 may be mounted in the branch pipe m , said pressure operated valve opening automatically if at decreasing 35 load the pressure in pipe a increases. If instead of the reduction of the losses from throttling produced by the use of the automatic governing by nozzles the advantage of the easier observation of the service is preferred, only one valve n and one valve i are arranged 40 and auxiliary valves adapted to be closed by hand and connected with the pipes a and o are preferably used when a lower or higher load than the normal average load 45 on the turbine lasts for a longer time.

I claim:—

1. In a steam plant, in combination, a source of steam, a motor, an accumulator, a passage for steam from said source to said 50 accumulator, a throttling valve controlling said passage, a passage for steam from said accumulator to said motor, a throttling valve controlling the last mentioned passage, means to conduct steam from said source to said motor, and means responsive to the speed of said motor to control said throttling valves.

2. In a steam plant, in combination, a source of steam, a motor, an accumulator, a passage for steam from said source to said 60 accumulator, a throttling valve controlling said passage, a passage for steam from said accumulator to said motor, a throttling valve controlling the last mentioned passage, means to conduct steam from said source to

said motor, and means responsive to the speed of said motor and operating to hold both said throttling valves closed at a given speed, to open the first-mentioned throttling valve when the speed of the motor increases 70 above said given speed and to open the second-mentioned throttling valve when the speed of the motor decreases below said given speed.

3. In a steam plant, in combination, a source of steam, a motor having a clear uninterrupted passage for steam through the same, an accumulator, a passage for steam from said source to said accumulator, a throttling valve controlling said passage, a 75 passage for steam from said accumulator to said motor, a throttling valve controlling the last-mentioned passage, means to conduct steam from said source to said motor and means responsive to the speed of said motor 80 to control said throttling valves.

4. In a steam plant, in combination, a source of steam, a motor, an accumulator, a passage for steam from said source to and through said motor, a passage for steam 85 from said source to said accumulator, a throttling valve controlling the last-mentioned passage, a separate supply chamber in said motor, a passage for steam from said accumulator to said separate supply chamber, a throttling valve controlling the last-mentioned passage and means responsive to the speed of said motor to control said throttling valves.

5. In a steam plant, in combination, a source of steam, a motor, an accumulator, a passage for steam from said source to and through said motor, a passage for steam from said source to said accumulator, a throttling valve controlling the last-mentioned passage, a separate supply chamber in said motor, a passage for steam from said accumulator to said separate supply chamber, a throttling valve controlling the last-mentioned passage and means responsive to the speed of said motor operating to hold both said throttling valves closed at a given speed, to open the first-mentioned throttling valve when the speed of the motor increases 100 above said given speed and to open the second-mentioned valve when the speed of the motor decreases below said given speed.

6. In a steam plant, in combination, a motor having a plurality of stages including a low pressure stage, a source of steam, two parallel paths for steam from said source to said low pressure stage, one of said paths including an accumulator and means responsive to the speed of said motor to wholly cut off supply of steam to and discharge of steam from the accumulator while permitting passage of steam through the path parallel to the accumulator.

7. In a steam plant, in combination, a motor, an accumulator, means to conduct

steam from said accumulator to said motor, means to supply steam to said motor and to said accumulator, said motor being arranged so that steam may pass through the same, and means responsive to speed of the motor to wholly cut off the accumulator from the motor at a given normal motor speed while simultaneously permitting passage of steam through the motor.

13. In a steam plant, in combination, a turbine comprising a plurality of stages, a series of nozzles in front of one of said stages, an accumulator, means to supply steam from said accumulator to said nozzles, means to supply steam to said accumulator, speed responsive means to control flow of

16 8. In a steam plant, in combination, a
motor and an accumulator, a source of steam
supplying steam to said motor and to said
accumulator, a discharge conduit conduct-
ing steam from the accumulator to the motor
15 and means responsive to the speed of said
motor to simultaneously cut off the supply
of steam to the accumulator and the dis-
charge conduit from the accumulator.

9. In a steam plant, in combination, a
20 motor, a steam accumulator, means to sup-
ply steam to the motor, a supply conduit ex-
tending from said motor to said accumu-
lator, a discharge conduit extending from
said accumulator to said motor, means
25 whereby at a given normal speed the steam
flow through the supply and discharge con-
duits is cut off while steam is permitted to
flow through the motor.

10. In a steam plant, in combination, a
30 motor comprising a plurality of stages, an
accumulator supplied with steam from a
point ahead of one of the stages and deliver-
ing steam to a point ahead of another stage,
means responsive to the speed of said motor
35 to cut off communication between the ac-
cumulator and motor at a given motor speed,
means to open communication from said ac-
cumulator to said motor but preventing flow
of steam into the accumulator at decreased
40 speed, and means to open communication to
permit flow of steam into said accumulator
and cutting off flow of steam from said ac-
cumulator to said motor at increased speed.

45 11. In a steam plant, in combination, a motor comprising a plurality of stages, an accumulator supplied with steam from a point ahead of one of the stages and delivering steam to a point ahead of another stage, means to cut off communication between the

50 means to open communication between the accumulator and motor at a given speed, means to open communication from said accumulator to said motor but preventing flow of steam into the accumulator at decreased speed, and means to open communication to permit flow of steam into said accumulator and cutting off flow of steam from said accumulator to said motor at increased speed, and a centrifugal governor responsive to the speed of the motor to control said means.

55

60

60 12. In a steam plant, in combination, a
motor comprising a plurality of stages, an
accumulator coupled in parallel to one or
more stages of the motor, automatic means
65 responsive to the speed of said motor to con-
trol passage of steam into and out of the

accumulator and a clear uninterrupted passage for steam through the motor.

13. In a steam plant, in combination, a turbine comprising a plurality of stages, a series of nozzles in front of one of said stages, an accumulator, means to supply steam from said accumulator to said nozzles, means to supply steam to said accumulator, speed responsive means to control flow of steam through said nozzles, said speed responsive means operating to cut off said flow at a given normal speed of the turbine while permitting steam to flow through the motor.

14. In a steam plant, in combination, a 80
motor having a high pressure stage, an intermediate pressure stage and a low pressure stage, a first chamber between said high pressure stage and said intermediate stage, a second chamber between said intermediate stage and said low pressure stage, an 85 accumulator, a conduit between said first chamber and said accumulator, a throttle valve in said conduit, a conduit between said second chamber and said accumulator, a throttle valve in the last mentioned conduit, and means responsive to the speed of said 90 motor to operate the throttling valves.

15. In a steam plant, in combination, a motor having a high pressure stage, an intermediate pressure stage and a low pressure stage, a first chamber between said high pressure stage and said intermediate stage, a second chamber between said intermediate stage and said low pressure stage, an accumulator, a conduit between said first chamber and said accumulator, a throttle valve in said conduit, a conduit between said second chamber and said accumulator, a throttle valve in the last mentioned conduit, and means responsive to the speed of said motor and operating to hold both said throttling valves closed at a given speed, to open the first-mentioned throttling valve when the speed of the motor increases above said given speed and to open the second-mentioned throttling valve when the speed of the motor decreases below said given speed. 110

16. In a steam plant, in combination, a 115
motor having a high pressure stage, an intermediate stage, a low pressure stage, a first chamber between said high pressure stage and said intermediate stage, a second chamber 120 between said intermediate stage and said low pressure stage, a separate chamber for supplying steam to said low pressure stage, an accumulator, a conduit between said first chamber and said accumulator, a throttle valve in said conduit, a passage for 125 steam from said accumulator to said separate chamber, a throttle valve to control flow through said passage and means responsive to the speed of said motor to operate the throttling valves. 130

17. In a steam plant, in combination, a source of steam, a motor, an accumulator, a passage for steam from said source to said accumulator, a throttling valve controlling said passage, a passage for steam from said 5 accumulator to said motor, a throttling valve in the last-mentioned passage, means to conduct steam from said source to said motor, means to supply steam to said source, means responsive to the speed of said motor operating to hold said throttling valve closed at a given speed, to open the first-mentioned throttling valve when the speed of the motor increases above said given speed and to open 10 the second-mentioned throttling valve when the speed of the motor decreases below said given speed, and means to diminish the supply of steam to said source when the speed of the motor rises above a predetermined 15 high value.
18. In a steam plant, in combination, a source of steam, a motor, an accumulator, a passage for steam from said source to said accumulator, a throttling valve controlling said passage, a passage for steam from said 20 accumulator to said motor, a throttling valve in the last-mentioned passage, means to conduct steam from said source to said motor, means to supply steam to said source, means responsive to the speed of said motor operating to hold both said throttling valves closed at a given speed, to open the first-mentioned throttling valve when the speed of the motor increases above said given speed and 25 to open the second-mentioned throttling valve when the speed of the motor decreases below said given speed, and a clear uninterrupted passage for steam through the motor.
19. In a steam plant, in combination, a source of steam, a motor, an accumulator, a passage for steam from said source to said accumulator, a throttling valve controlling said passage, a passage for steam from said 30 accumulator to said motor, a throttling valve in the last-mentioned passage, means to conduct steam from said source to said motor, means to supply steam to said source, means responsive to the speed of said motor operating to hold both said throttling valves closed at a given speed, to open the first-mentioned throttling valve when the speed of the motor increases above said given speed and 35 to open the second-mentioned throttling valve when the speed of the motor decreases below said given speed, a clear uninterrupted passage for steam through the motor.
20. In a steam plant, in combination, a motor having a plurality of stages, a chamber between two of said stages, a source of steam, an accumulator, a passage for steam 40 from said source to said accumulator, a throttling valve controlling said passage, a passage for steam from said source to said motor, a throttling valve controlling the last-mentioned passage, a conduit for steam from said accumulator to said chamber, a throttling valve in said conduit, and means responsive to the speed of said motor for controlling said throttling valves.
21. In a steam plant, in combination, a motor having a plurality of stages, a chamber between two of said stages, a source of steam, an accumulator, a passage for steam from said source to said accumulator, a throttling valve controlling said passage, a passage for steam from said source to said 45 motor, a throttling valve controlling the last-mentioned passage, a conduit for steam from said accumulator to said chamber, a throttling valve in said conduit, and means responsive to the speed of said motor operating to hold the first-mentioned and third-mentioned throttling valves closed at a given speed of the motor, to open the first-mentioned throttle valve when the speed of the motor increases above said given speed and 50 to open the third-mentioned throttling valve when the speed of the motor decreases below said given speed.
22. In a steam plant, in combination, a motor, an accumulator, a conduit to conduct steam from said motor to said accumulator, a conduit to conduct steam from said accumulator to said motor and throttle valves within and controlling each of said conduits, said conduits being the only conduits 55 communicating between the accumulator and the motor, so that the motor may be substantially independent of pressure variations in said accumulator.
23. In a steam plant, in combination, a motor, an accumulator, a plurality of conduits connecting said accumulator with said motor, one of which conduits leads steam from said accumulator to said motor and one of which conduits leads steam from said 60 motor to said accumulator, and a throttle valve within and controlling each of said conduits, said conduits being the only conduits communicating between the accumulator and the motor so that the motor may be substantially independent of variations of pressure in said accumulator.
24. In a steam plant, in combination, a source of steam, a motor, an accumulator, a plurality of conduits interconnecting said source, motor and accumulator, one of which conduits leads steam from the source to the accumulator and one of which conduits leads steam from the accumulator to the motor, and a throttle valve within each of the conduits interconnecting the accumulator with either the source or the motor so that the motor may be made substantially 65 independent of variations of pressure in said accumulator.

25. In a steam motor plant, in combination, a motor having a plurality of stages including a low pressure stage, a source of steam, two parallel paths for steam from 5 said source to said low pressure stage, one of said paths including an accumulator and means responsive to variations of load conditions in the motor plant to wholly cut off communication between said accumulator 10 and said motor while the motor operates at a substantial value of balance of plant load.
26. In a steam motor plant, in combination, a motor, an accumulator, a plurality of conduits connecting said accumulator 15 with said motor, one of which conduits leads steam from said accumulator to said motor and one of which conduits leads steam from said motor to said accumulator, throttling valves within and controlling each of said conduits, said conduits being the only conduits communicating between the accumulator and the motor so that the motor may be substantially independent of variations of pressure in said accumulator and means responsive to variations of load conditions 20 in the motor plant to control said throttling valves and operating to wholly cut off communication through each and all of said conduits between said accumulator and said motor and between said motor and said accumulator while the motor operates at a substantial value of balance of plant load.
